SCUFF PLATE

Clifford B. Doty, Detroit, Mich., assignor to
 Briggs Manufacturing Company, Detroit,
 Mich., a corporation of Michigan

Application May 22, 1939, Serial No. 274,926

10 Claims. (Cl. 296—28)

This invention relates to vehicle bodies and particularly to a scuff plate unit or assembly adapted to be applied to the door sill of the body at the lower edge of the door opening.

5 An object of the invention is to provide a relatively simple, inexpensive and ornamental unit of the foregoing character in which the parts of the unit are capable of easy assembly, and in which the assembled unit is capable of easy and 10 quick application to the vehicle.

A further object is to provide a scuff plate assembly comprising a supporting member and a face or escutcheon plate adapted to cover an exposed portion of the supporting member and 15 providing means to overlie and hold down the edge of the floor covering at the door sill.

20 Another object is to provide a two-part scuff plate assembly comprising a supporting member which may be mounted upon the door sill and which has an upstanding wall preferably bent inwardly to overlie the edge of a floor covering, and also comprising a face or escutcheon plate adapted to clasp or embrace the wall, such as by 25 means of interlocking or interfitting parts, and wherein the face plate is preferably provided with a depending skirt capable of concealing an exposed portion of the body sill.

25 Another object of the invention is to provide a scuff plate unit which is ornamental in character and which serves to conceal the edge of the floor covering within the door opening and to also conceal a portion of the adjacent frame member within the door opening.

30 Another object of the invention is to provide a scuff plate assembly of the foregoing type in which the supporting member thereof is formed of relatively stiff heavy gage metal and in which the face plate of the assembly is formed of relatively lighter gage and more flexible metal.

35 The above and other objects and advantages of this invention will appear in the following description and appended claims, reference being had to the accompanying drawing forming a part of this specification wherein like reference characters designate corresponding parts in the several views.

In said drawing:

40 Fig. 1 is a side elevational view of an automobile equipped with the improved scuff plate in accordance with the present invention.

45 Fig. 2 is an enlarged fragmentary sectional view taken substantially along the line 2—2 of Fig. 1, looking in the direction of the arrows.

50 Fig. 3 is an enlarged view of the scuff plate embodying one form of the present invention

and shown in Fig. 2, illustrating in broken lines one method of assembling the component parts of the scuff plate.

Fig. 4 is a view similar to Fig. 2 illustrating a somewhat modified form of scuff plate structure; and

Fig. 5 is a view similar to Fig. 3, showing the scuff plate of Fig. 4.

Before explaining in detail the present invention it is to be understood that the invention 10 is not limited in its application to the details of construction and arrangement of parts illustrated in the accompanying drawing, since the invention is capable of other embodiments and of being practiced or carried out in various ways. 15 Also it is to be understood that the phraseology or terminology employed herein is for the purpose of description and not of limitation, and it is not intended to limit the invention claimed herein beyond the requirements of the prior art. 20

25 Referring now to the drawing, and particularly to Figs. 1 to 3 inclusive thereof wherein a preferred embodiment of the invention is shown, 10 represents a longitudinal frame member of the vehicle body which has a substantially horizontal inwardly directed flange 11 to which the vehicle body floor may be attached. A door sill member of the body is shown as a whole at 12 and includes an upright leg portion or section 13 and a substantially horizontally disposed extension 25 or flange 14 which overlies and rests upon the flange 11. The door herein illustrated is shown as a whole at 15 and comprises an outer panel 16 having a lower extension and an inner panel 17 which is joined at its lower end to the outer panel. A trim panel 18 is applied to the exposed face of the inner panel 17 in conventional manner. The lower extensions of the inner and outer panels where joined serve to support a rubber or other flexible sealing strip or member 19 which, as shown, abuts the outer adjacent face of the frame member or sill 12 and is deformed when the door is in closed position as shown. In the form of the invention illustrated in Fig. 4, the trim panel 18 is provided with a windlace 20 which abuts a portion of the scuff plate as will be seen hereinafter.

30 The scuff plate unit is indicated as a whole at A and comprises, as shown, a supporting member provided with a substantially horizontal base 30 having an arched rib portion 31 providing an underlying groove or channel. The support, as shown, is bent upon itself to provide a double wall fold or flange 32 and extends in an upward direction to provide a backing wall 33. The top 35

portion of the wall 33 is crowned or arched at 34 and terminates in a downwardly and inwardly directed edge 35.

As shown in Fig. 2, the carpet or other floor covering 40 rests upon the base 30 of the scuff plate support, the base of the support having been preferably first attached to the flanges 14 and 11 by a series of nails, screws, or the like 36.

The face or escutcheon plate of the present embodiment comprises, as shown, an upright portion or section 50 having an integral curved or crowned portion 51 which terminates in an inwardly directed edge flange or lip 52. As seen in broken lines, Fig. 3, the scuff plate or member 15 has an integral return bent flange 53 which extends substantially perpendicularly to the portion 50 and is extended to provide a convex or bowed skirt section 54 which, as shown in Figs. 2 and 3, curves outwardly and downwardly and then slightly inwardly with respect to the frame members 10 and 12, and terminates in a free edge 55.

As indicated by the arrow in Fig. 3, one manner of assembling the scuff plate proper with the supporting member of the unit A is by hooking the longitudinal edge flange 52 over the free longitudinal edge 35 of the support, pressing the body portion 50 of the scuff plate inwardly to bring the flange 53 into position beneath the portions 31 and 32 of the support and then pressing or rolling the flange 53 upwardly and outwardly with relation to the base 30 so that it will clinch or tightly engage the flange 32 of the support, assuming the position in which it is shown in full lines at 53a in Fig. 3. The assembled parts forming the scuff plate unit of the present form of the invention may then be applied to the sill flange 14 and secured thereto by the screws or nails 36. In this position, the convexly curved depending skirt or lower section 54 of the scuff plate overlies and conceals the portion 13 of the sill member with its lower edge 55 preferably contacting the outer face of said portion in such manner as to hold the skirt in fixed or sprung condition. Thus the scuff plate not only serves as an ornamental member to conceal the edge of the floor covering 40 and to maintain said covering in smooth condition adjacent the door opening, but likewise covers 50 and conceals the upright upper portion 13 of the sill. If desirable, stainless steel may be employed to make the scuff or face plate, although other metals can be used and chrome plated or lacquered in a color which blends or harmonizes with the body finish.

While one method of assembling the scuff plate with its support has been illustrated in Fig. 3, it will be understood that the curved flange such as that shown at 53a can be formed prior to the assembly of the supporting member and the two members assembled by telescoping one over the other.

In Figs. 4 and 5 a somewhat modified form of scuff plate unit embodying the present invention is illustrated and, as stated above, in this embodiment the trim panel 18 is provided with the windlace 20 which, when the door is closed as shown in Fig. 4, is wedged or compressed between the adjacent face of the inner panel 17 and the upper portion of the scuff plate and its support. As in the preceding form, the remaining portions of the door and the vehicle frame members 10, 12, etc., are identical. The scuff plate of the present form is shown as a whole at B.

The supporting member of the scuff plate unit of Figs. 4 and 5 comprises a base 130 which is formed with a curved rib portion 131 providing an underlying longitudinal recess or pocket 131a. The rib 131 terminates at the point 132 and the metal is bent in a reverse direction to provide an upright integral portion 133, and a convex, arched or crowned portion 134 which terminates in a free edge 135. The arched portion 134 and the edge 135 are spaced above and overlie the 10 portions 130 and 131.

The scuff or face plate proper of the unit of the present form of the invention comprises a metal plate having a straight portion or section 150, a convexly curved or crowned portion 151 and an inturned longitudinal flange or lip 152. The metal of the plate is bent or formed to provide a longitudinally extending substantially U-shaped bead or rib 153. The lower leg or portion 153a of the bead 153 is extended outwardly and downwardly to provide a skirt 154 and terminates in an inwardly directed free edge 155.

There is illustrated in broken lines, Fig. 5, one method of applying the scuff plate of the unit to the supporting member therefor. The flanged edge 152 is hooked over the edge 135 of the support and the plate is pressed or forced inwardly toward the support as indicated by the arrow. The wall 50 and the rib or bead 153, 153a will 30 flex or spring sufficiently to permit the bead to pass the edge 132 of the supporting member and cause the bead 153 to be snapped into place within the recess 131a and yieldingly held in position as shown in Fig. 5. In this position, referring particularly to Fig. 4, the lower edge 155 of the plate member will engage the upright portion 13 of the sill member. Thus the support and the edge of the floor covering 40 will be entirely concealed from view and the portion 153 40 of the plate will conceal a major part of the upright portion 13 of the sill.

The unit of Figs. 4 and 5 is preferably applied to the vehicle body of securing the base 130 of the support to the flanges 11 and 14 by means 45 of nails or screws 136. The plate is then applied to the support in the manner above described. It will be seen, Fig. 4, that the flange or angularly disposed lip 152 will rest upon the floor covering 40. The unit will thus serve to maintain the 50 floor covering in place at the door opening as well as to conceal the edge of the floor covering.

It will be understood that the support and the plate of Figs. 4 and 5 may be assembled in other ways than that above described. For example, 55 the parts could be telescoped over one another by sliding the plate longitudinally relatively to the support prior to the application of the unit to the vehicle body.

From the foregoing it will be seen that the 60 scuff plate member of the unit may be assembled with and attached to the supporting member of the unit by merely snapping it into place. It will be seen that the supporting member may be formed of relatively stiff heavy gage metal 65 whereas the face plate may be formed of relatively light gage springy metal. This permits the ready application of the scuff plate to its support.

While it is intended in practice that the face 70 plate and the supported member therefor of both forms of the present invention will remain together as a unit once they have been assembled, it is to be noted that by virtue of the formation of the scuff plate and its supporting mem- 75

ber as shown in Fig. 5, it is possible to remove the plate from its support by prying it loose from its support.

I claim:

5. 1. A scuff plate for a vehicle door opening, comprising a support adapted to be mounted on the sill and having a portion adapted to overlie an edge of the floor covering, and a face plate carried by said support, said support and face plate having cooperating interfitting means for holding them together as a unit and said face plate having a skirt extended downwardly from the support and concealing a portion of said sill.

10. 2. A scuff plate comprising a support adapted to be mounted upon a vehicle body sill at a door opening thereof and comprising an upright backing portion, and an escutcheon plate covering the outer face of the backing portion and interlocked therewith, said backing portion being 15 extended inwardly of the sill to overlie the edge of a floor covering and said escutcheon plate having a flexible skirt extended downwardly below said backing portion and concealing a portion of said body sill.

20. 3. A scuff plate unit for a vehicle door opening, comprising a support for mounting upon a frame member of the vehicle, said support having a base portion and an upright extension, and a face plate attached to and carried by said support, said face plate having a portion engaging said upright extension and a skirt portion engaging said frame member.

25. 4. A scuff plate unit for a vehicle door opening, comprising a support for mounting upon a frame member of the vehicle, said support having a base portion and an upright portion, and a face plate attached to and carried by said support, said face plate having a portion engaging the upright portion of the support and a skirt portion engaging said frame member, said support and said face plate having interfitting means for holding the parts together.

30. 5. A scuff plate unit for a vehicle door opening, comprising a support mounted upon a frame member of the vehicle, said support having a base portion, an integral upright extension and an inwardly extending crowned portion, said crowned portion being spaced from and overlying said base portion, and an ornamental member attached to and covering said extension, said

member having a depending skirt portion extending downwardly from said base portion and concealing a portion of said frame member.

35. 6. In a scuff plate unit for a vehicle door opening, the combination of an elongated support for mounting upon a frame member of the vehicle, said support having a base and an upright integral extension, and a face plate carried by the support, said face plate having a portion extending upwardly above said base and covering said 10 extension, said face plate also having a depending skirt portion extending below said base and engaging said frame member, said base having a recess formed therein and said plate having a flange engaging said recess to hold the parts together.

40. 7. A scuff plate assembly for a vehicle door opening comprising a support for mounting upon a frame member of the vehicle, said support having a base portion and an upright wall extended 20 inwardly in spaced relation to the base portion to provide a free edge engageable with a floor covering, and a face plate attached to and carried by said support, said face plate having a portion covering said wall and a depending skirt portion 25 adapted to engage and conceal a part of said frame member, said support having a longitudinally extending recess formed therein and said plate having a longitudinally extending rib engaging said recess to hold the parts together.

45. 8. A scuff plate assembly according to claim 7 in which the face plate has an edge flange hooked over the free edge of said wall and in which said rib is forced into the recess by spring action to releasably interlock the parts together.

50. 9. A scuff plate assembly according to claim 7 in which said rib is bent up into the recess to interlock the parts together.

10. A scuff plate assembly comprising a supporting member adapted to be mounted upon a vehicle body sill and provided with an upstanding wall extended inwardly in spaced relation to the sill to overlie the edge of a floor covering, and a face plate attached to said member and covering said wall, said face plate having an upper portion substantially coextensive with said wall and a lower portion providing a flexible depending skirt.

CLIFFORD B. DOTY.
